MECHANISM FOR ADJUSTING THE BRUSH HEIGHT IN CARPET SWEEPERS

John M. Himes, Hartford, and Jerry W. Poad, Milwaukee, Wis., assignors to E. R. Wagner Manufacturing Company, Milwaukee, Wis., a corporation of Wisconsin

Filed June 24, 1963, Ser. No. 289,922

9 Claims. (Cl. 15—41)

This invention relates to improvements in mechanisms for adjusting the brush height in carpet sweepers.

The principal object of this invention is to provide a dial operated carpet sweeper brush height adjustment mechanism which will permit several intermediate height settings between a maximum height, as required for thick nap carpets, and between a minimum height, as required for close nap carpets or bare floors.

A further object of this invention is to provide a dial operated carpet sweeper brush height adjustment mechanism in which the knob of the dial is located on the top exterior wall of the carpet sweeper housing to render the same easily visible and accessible to the user.

A still further object of this invention is to provide an adjustment mechanism having the above described advantages without sacrificing or impairing any of the desirable features of the heretofore known high quality carpet sweepers, and without significantly increasing the cost of a carpet sweeper by virtue of the adjustment mechanism.

These objects are attained by a mechanism which is responsive to the selective turning of a knob located on the top exterior of the carpet sweeper housing and by means of which a crankshaft may be actuated to limit or vary the lowest position of the brush. By limiting only the lower position, it is possible to still maintain the advantage of spring loading the brush to thereby prevent stalling of the sweeper upon encountering some irregularities of the carpet or small object inadvertently left thereon.

Other objects and advantages will be pointed out in, or be apparent from, the specification and claims, as will obvious modifications of the single embodiment shown in the drawings, in which:

FIG. 1 is a top plan view of a carpet sweeper embodying the present invention, with only a fragment of the handle being shown;

FIG. 2 is a vertical cross sectional view of the carpet sweeper shown in FIG. 1 in which one of the end bells has been removed to show the floor wheels and the brush;

FIG. 3 is a view in vertical cross section taken on line 3—3 of FIG. 1 showing the brush height adjustment mechanism at the highest brush height setting, the floor wheels and brush pulley being superimposed and shown in dashed lines to better illustrate the cooperation of these parts;

FIG. 4 is a view as shown in FIG. 3, but having the brush height adjustment at the lowest brush height setting;

FIG. 5 is a fragmentary cross sectional view taken on line 5—5 of FIG. 3;

FIG. 6 is a fragmentary side view of the knob and the cam housing;

FIG. 7 is a cross sectional view of the cam housing;

FIGS. 8 and 9 show the cam in side elevation;

FIG. 10 is a bottom plan view of the knob;

FIG. 11 is a view taken on line 11—11 of FIG. 7;

FIG. 12 is a fractional bottom plan view of the cam and adjustment rod with part of the cam housing being broken away; and

FIG. 13 is a side view of the brush slide.

The drawings illustrate a carpet sweeper of which the basic elements and principles of operation are well-known in the art and are in general disclosed in the U.S. patent

issued to Swift Miller Patent Number 2,121,880. The invention resides in replacing the brush height adjustment disclosed in the aforementioned patent by an adjustment mechanism which is responsive to the turning of a knob 10 to any one of a number of positions between the highest and lowest settings to thereby provide corresponding height settings of the brush 12 of the sweeper. Further, the mechanism is designed to permit the knob 10 to be centrally located on the top exterior surface of the carpet sweeper housing 14.

The carpet sweeper has floor engaging wheels 16 which frictionally engage pulleys 20 secured on each end of the brush 12. The floor wheels are mounted for limited vertical motion and are biased downwardly by springs 21. Upon motion of the carpet sweeper along a floor or carpet, the wheels impart rotary motion by means of the pulleys 20 to thereby cause the brush to sweep up dust and deposit the same in suitable dust pans provided within the carpet sweeper housing.

Brush slides 22 having trunnions 24 for engagement with sockets 25 of the brush axle 26 are attached by pins 28 to each of the bell caps 30 disposed on the sides of the housing. Each slide is provided with elongated slot 32 for reception of the pin 28 to thereby permit some limited vertical motion of the slide. Each slide is further guided by a contoured and depressed portion 34 in the bell cap. It is of note that by virtue of the contoured portion a corresponding elongated slot 38 has to be provided in the bell cap for reception of the trunnion 24.

As best seen from FIG. 3 a wire spring 38 is retained within the bell cap by eyelet members 40 and engages a projection 42 of the slide to exert a normally downward bias thereon.

In normal operation of the sweeper the spring 38 pushes the brush 12 downwardly to cause the same to enter the carpet and thereby cause the brush bristles to bend slightly and give a flicking action. The spring allows the bristles to rise for any condition which would require the bristles to bend more than planned, and in this manner permits the brush to ride over the obstruction. In absence of this feature the pulley would tend to bind and prevent rotation of both floor wheels 16.

As best seen from FIGS. 3 and 4, the lower limit of the vertical travel of the brush is controlled by the wedge surface 44 of lever 46 which engages the bottom side of the projection 42. By varying the position of the wedge surface 44, the effective brush height will be correspondingly varied while still maintaining the feature of permitting the brush to rise against the bias of the spring 38 upon encountering an obstruction on the floor.

An adjustment rod 48 is transversely disposed within the housing and retained for rotation around its longitudinal axis by side wall 50 of the housing. A crank arm 52 is provided on each end of the adjustment rod and is engaged with one end of the lever 46 to impart motion thereto upon rotation of the adjustment rod around its longitudinal axis (indicated at A in FIGS. 2 and 3). The other end of the lever is provided with an elongated slot 54 which is engaged by the pin 28. As is apparent, when comparing FIGS. 2 and 3, the rotation of the crank arm in a clockwise direction when viewed in these figures will cause a downward movement of the wedge surface 44 thereby permitting the spring 38 to bias the brush 12 to its lowermost position. Also a rotation in the opposite direction will cause the wedge surface 44 to force the projection 42 of the axle link upwardly and thus limit the amount of vertical travel permitted by the brush. It is apparent that the vertical location of the wedge surface 44 is dependent upon the degree of turn of the crankshaft 52 around its axis and that therefore the brush height (i.e. vertical location of projection 42) can be set

at any desired position between those shown in FIG. 4 and FIG. 3.

At its center the adjustment rod 48 is provided with a transversely extending section 54 which is engaged by a cam 56 and may be moved in response to the rotation of the cam between the two positions shown in FIG. 7.

The knob 10 is rotatably secured to the top surface 14 of the carpet sweeper housing and is secured to the cam 56 by means of three nibs 58 which engage corresponding apertures in the bottom face 60 of the cam and thus cause the knob and cam to rotate as a unit. The knob overlies a dial face 62 on which the various brush heights are indicated and is provided with a pointer 64 to show the position of the brush. The brush height settings on the dial may be, of course, indicated in the terms of the type of nap for which the particular brush height setting is suitable, as for example, close nap, medium nap, and thick nap. Resilient element 66 having a projection 68 is provided on the bottom face 70 of the knob and cooperates with apertures 72 in the housing wall to permit indexing of the knob. The projection engages the apertures with sufficient force to prevent unintended movement of the dial during normal operation of the carpet sweeper, yet permits easy turning of the dial by hand when it is desired to change the brush height settings. A stop member 74 cooperates with a groove 76 in the knob to limit the rotary motion of the knob between the high brush and the low brush settings.

To prevent dust and dirt from interfering with the operation of the cam, the cam and its related structure are enclosed in a cam housing 78. The housing is comprised of two sheet metal members 80 and 82 which are secured to each other by means of tabs 86. One of the members is provided with notches 88 which receive the adjustment rod.

From the above description it should be apparent that the brush height adjustment mechanism embodying the present invention is operable to effectively limit the vertical downward travel of the brush 12 without impairing the spring loading of the brush which is required to prevent stalling when encountering an obstruction in the path of the carpet sweeper.

Further it is of note that the brush settings may be varied by the easily accessible and visible knob 10 which is located on the top surface of the housing and may be indexed to provide incremental adjustment of the brush height as required for the particular surface desired to be swept.

Although but one embodiment of the present invention has been illustrated and described, it will be apparent to those skilled in the art that various changes and modifications may be made therein without departing from the spirit of the invention or from the scope of the appended claims.

We claim:

1. A carpet sweeper comprising, a wheeled housing, a brush and two slides, said brush being rotatably mounted at each end on one of said slides and said slides being secured for limited vertical motion to said housing to thereby permit said brush to ride over small obstructions which might be encountered on the surface to be swept, biasing means urging said brush and slides downwardly, stop means limiting the extent of permissible downward travel of said brush, a knob rotatably carried by said housing, and a crankshaft operably connected to said stop

means and said knob to vary the position of said stop means to a plurality of positions to thereby selectively change the lowest position to which said brush may be biased by said biasing means yet to permit the upward travel required to ride over said small obstructions.

2. A carpet sweeper according to claim 1 having indexing means adapted to retain said knob on any one of a number of preselected positions.

3. A carpet sweeper according to claim 2 wherein said knob is located between the ends of said crankshaft and wherein said knob carries cam means operable to rotate said crankshaft upon rotation of said knob.

4. A carpet sweeper according to claim 3 wherein said cam means comprises a cylindrical member having a slanted end portion, said end portion engaging a section of said crankshaft which extends transversely to the longitudinal axis of said crankshaft.

5. A carpet sweeper comprising, a wheeled housing, a brush and two slides, said brush being rotatably mounted at each end on one of said slides and said slides being secured for limited vertical motion to said housing to thereby permit said brush to ride over small obstructions which might be encountered on the surface to be swept, biasing means urging said brush and slides downwardly, two control levers each operable to engage one of said slides and limit the extent of their downward travel, a crankshaft carried by said housing and secured at each of its ends to one of said control levers, a knob mounted on said housing and having cam means operable to rotate said crankshaft in response to rotation of said knob, said crankshaft changing the position of said control levers in response to the rotation of said knob to thereby change the lowest position to which said brush may be biased.

6. A carpet sweeper according to claim 5 wherein said knob is located between the two ends of said crankshaft and is mounted in an upwardly facing position.

7. A carpet sweeper according to claim 6 wherein said cam means engage a portion of said crankshaft which extends transversely to the longitudinal axis of said crankshaft.

8. A carpet sweeper according to claim 7 wherein said knob has indexing means for retaining said knob in any one of a plurality of preselected positions between the high and low positions of said brushes.

9. A carpet sweeper comprising, a housing, a brush, said brush being rotatably mounted in said housing, brush driving wheels carried in said housing and vertically movable relative to said brush, spring means for biasing said relative vertical movement, laterally spaced stop means limiting the extent of said relative vertical movement, a knob rotatably carried by said housing, and a crankshaft operably connected to said each of said spaced stop means and said knob and rotatable by said knob to vary the position of said stop means to a plurality of positions to thereby selectively change the limits of said relative vertical movement.
